[57] ABSTRACT

A calculating machine for executing addition, subtrac-

tion, multiplication and division wherein a number set into the machine is printed as an effective number in accordance with the decimal orders of the calculating machine for visual observation in addition or subtraction characterized by the provision of a dividend introduction mechanism and by that after setting a dividend in a pin box and depressing a division () key:

1. a type bar is moved upwardly in the first half rotation of the first rotation of a main shaft without transferring the dividend to an accumulator so that the dividend is printed in such a manner that the least significant digit of the effective number representing the first decimal order of the dividend coincides with a position of the least significant digit of an effective number in addition or subtraction;
  2. in the last half of said first rotation of said main shaft, said pin box is shifted in such a manner that the most significant digit of the dividend set in said pin box may be transferred to a position of the most significant digit of a number or total in said accumulator;
  3. during the second rotation of said main shaft, the dividend is opposed into said accumulator in such a manner that the most significant digit of the dividend is transferred in the most significant digit of the number or total in said accumulator; and
  4. during the second rotation of said main shaft, caution pinions are cleared and reset to zeros.

**MECHANICAL CALCULATING APPARATUS FOR
ADDING, SUBTRACTING, MULTIPLYING AND
DIVIDING**

BACKGROUND OF THE INVENTION

The present invention relates to an electrically driven calculating machine for executing addition, subtraction, multiplication and division and more particularly a division mechanism and a printing mechanism for division.

In the conventional calculating machine, first a dividend is set and the most significant digit of this dividend is printed at a position corresponding to the printing of the most significant digit as normally printed in addition and subtraction in the calculating machine and zeros (0) are continuously printed from the digit next to the least significant digit of the dividend. Therefore, it is difficult to read the true values of the dividend and the quotient. Thus, it is very inconvenient in practice.

One of the objects of the present invention is to provide an electric calculating machine compact in size and light in weight by simplifying the interrelation among the division and other mechanisms.

Another object of the present invention is to provide an electric calculating machine wherein a dividend and a divisor are so printed that the (effective) least significant digit of each of the dividend and divisor coincides with a position where the (effective) least significant digit of a number to be printed in addition or subtraction, thereby facilitating the reading of the true values of the dividend and the divisor.

SUMMARY OF THE INVENTION

According to the present invention, a dividend is printed in such a manner that the least significant digit thereof may coincide with a position of the least significant digit of an effective number to be printed in addition or subtraction. When a dividend is set and then a division (÷) key is depressed, in the first half of the first rotation of a main shaft, the dividend is printed in such a manner as described above. In the last half of said first rotation of the main shaft, a pin box in which the dividend is set is shifted so that the most significant digit of the dividend coincides with the most significant digit position of the calculating machine. In the first half of the second rotation of the main shaft, the transfer of a number into an accumulator is ready without printing. In the last half of the second rotation, the number is transferred into the accumulator, as in case of addition, in such a manner that the most significant digit of the dividend is transferred to the position of the most significant digit of the accumulator. In this case, no printing is made. In this step, the caution pinions are cleared or reset for the next calculation. Next, a divisor is set in the pin box. Upon depression of the equal (=) key, the least significant digit of the divisor is printed at a position of the most significant digit of an effective number in addition or subtraction. Thereafter, the division is executed and a quotient is obtained and transferred into the caution pinions. A remainder is also set to the caution pinions. The numbers set in the caution pinions are read out and printed upon depression of a quotient (Q) key.

BRIEF DESCRIPTION OF DRAWINGS:

- 5 FIG. 1 is a side view illustrating the interior of the machine with a cover removed;
- 5 FIG. 2 is a perspective view illustrating a number setting device and a carry device of a pin box;
- 5 FIG. 3 is a plan view of a key board;
- 10 FIG. 4 is an explanatory view for explaining the vertical movement of the type bar;
- 10 FIGS. 5A, 5B, 5C and 5D explain the operation of an accumulator;
- 15 FIG. 6A is a perspective view of a locating mechanism and an accumulator engagement mechanism;
- 15 FIGS. 6B1, 6B2, 6B3 and 6B4 explain the engagement of an engagement cam and with a grooved cam follower;
- 20 FIG. 7A is a perspective view of a motor drive mechanism;
- 20 FIG. 7B is a side view illustrating a clutch mechanism of the motor being disengaged;
- 25 FIG. 7C is a side view illustrating the engagement of the mechanism of FIG. 7B;
- 25 FIG. 7D is a side view illustrating a relation between a key and a motor release connector;
- 30 FIG. 8 is a plan view illustrating a locating fork mechanism and the accumulator engagement mechanism;
- 30 FIG. 9A is a perspective view of an accumulator engagement direction instruction mechanism;
- 35 FIGS. 9A, 9B, 9C, 9D and 9E explain the engagement of the mechanism of FIG. 9A;
- 35 FIG. 10A is a perspective view illustrating a printing mechanism;
- 35 FIG. 10B is a detailed view of one section of the mechanism of FIG. 10A;
- 40 FIG. 10C is an explanatory view of a zero printing mechanism;
- 40 FIG. 10D is an explanatory view of a sign printing mechanism;
- 45 FIG. 10E is a front view illustrating numerals, signs and other characters upon the type bars;
- 45 FIG. 11A is a perspective view illustrating the relation among the parts of control keys;
- 50 FIG. 11B is an explanatory view of the clutch mechanism in multiplication and division;
- 50 FIG. 12A is a perspective view of a multiplication mechanism;
- 55 FIG. 12B is a side view illustrating the engagement of the caution pinion with a sub-rack of the multiplication mechanism;
- 55 FIG. 12C is an explanatory view illustrating the disengagement of the caution pinion in the multiplication mechanism;
- 60 FIG. 13A is a side view illustrating a caution pinion and a transfer direction instruction mechanism;
- 60 FIG. 13B is a side view of a caution pinion;
- 65 FIG. 13C is a perspective view illustrating the multiplication and division mechanism;
- 65 FIG. 13D is a perspective view illustrating the arrangement of the caution pinions;
- 65 FIG. 13E is a perspective view illustrating the engagement of the caution pinion with the multiplication and division mechanism;
- 65 FIG. 14A is a side view of a multiplication and division operation set mechanism;

FIG. 14B is a side view illustrating one portion of the mechanism of FIG. 14A;

FIG. 15A is a perspective view of a pin box clear mechanism and a multiplication and division operation termination mechanism;

FIG. 15B and 15C are detailed views illustrating the essential parts of the mechanism of FIG. 15A;

FIG. 15D is an explanatory view of an auto-total mechanism;

FIG. 15E is a perspective view of a part of FIG. 15A.

FIG. 16A is a perspective view illustrating one portion of the multiplication and division operation set mechanism;

FIG. 16B is a side view of the mechanism of FIG. 16A;

FIG. 16C is a detailed view of one portion of the mechanism of FIG. 16A;

FIG. 17A is a perspective view illustrating one portion of the multiplication and division operation set mechanism;

FIG. 17B is an explanatory view of a non-printing mechanism;

FIG. 17C is an enlarged perspective view illustrating one portion of a detent plate;

FIG. 18A is a perspective view illustrating a caution pinion drive direction instruction mechanism;

FIG. 18B is a side view of the mechanism of FIG. 18A in multiplication;

FIG. 18C is a side view of the mechanism of FIG. 18A in division;

FIG. 18D is a detailed view of the mechanism of FIG. 18A;

FIG. 19 is an explanatory view of a shift-to-right mechanism in division;

FIG. 20 is a plan view of the pin box clear mechanism;

FIG. 21 is a side view of a caution pinion actuating mechanism;

FIG. 22A is a perspective view of a pin box clear auxiliary mechanism of the multiplication and division mechanism;

FIG. 22B is a perspective view of a detent mechanism;

FIG. 22C is a detailed perspective view of a decimal credit balance mechanism;

FIG. 23 is a plan view of a dividend introduction mechanism;

FIG. 24 is a side view of the mechanism of FIG. 23;

FIGS. 25A, 25B, 25C and 25D explain the actuation and associated parts of a division set lever;

FIG. 26 is a detailed plan view illustrating the essential parts of the dividend introduction mechanism;

FIG. 27A is a side view of the caution pinion drive mechanism when a number in the accumulator is positive in case of division;

FIG. 27B is similar to FIG. 27A except that a number in the accumulator is negative;

FIG. 28 is a plan view of a division termination mechanism; and

FIG. 29 is a side view of a quotient reading mechanism.

DESCRIPTION OF THE PREFERRED EMBODIMENT

Referring to FIGS. 1 to 3, the keyboard 2 is attached to a machine frame 1, and each key top 3 is fixed to its

key stem 4 which can slidably move in the key board 2 and 5 in the longitudinal direction. Each key is normally biased to move upwardly by means of a spring 6. A digit key 7 is slidably secured to the key stem 4 in such a manner as will be described in more detail hereinafter and terminates in front of a pin box 8. The keyboard side will be referred to as "front" throughout this specification. The total of 10 columns each consisting of eight slidable pins 10 and one pin 11 are arrayed upon the pin box 8 which rides upon a guide shaft 9.

Upon the keyboard, the key tops 3, corresponding to the digits from 1 to 9, and those 3a, corresponding to the digits "0," "00" and "000," are arrayed in three columns and four rows as best shown in FIG. 3. The key tops 3 are adapted to cause the pins 10 in the pin box 8 to slide backwardly when depressed through the digit keys 7 while the key tops 3a cause the pins 11 to slide through the digit keys 7a.

Each key top 3 causes the pin 10 and a press-up plate 12 to move in the longitudinal directions through the digit key 7, and the digit key for setting the digit 9 only acts upon the press-up plate 12 so as to move it toward the pin box 8. The press-up plate 12 causes a press-up lever 13 to rotate so that the pin box 8 which is locked by a heel 13b at 11 is released. (See FIG. 2).

A toothed member 14 and a finger 15 are formed at the upper portion of the pin box 8 in opposed relation to the press-up plate 12 and the finger 15 serves the function of the pin 10 when the digit 9 is set. The toothed member 14, the press-up plate 12, the press-up lever 13 and the pins 11 constitute the escapement which upon depression of the key top 3 on the keyboard 2 causes the pin box 8 to move to left by one tooth. By means of the pin 11 of the pin box 8 which is controlled by the key top 3a, the pin box 8 is directly released from the heel 13b of the press-up lever 13 so that the pin box 8 is moved by one, two or three digit spacings depending upon the depression of the key top of 0,00 or 000. As described above, the pin 10 is moved backwardly beyond the pin box 8 upon depression of its corresponding key. Thus, a number to be operated is set.

For carrying out the arithmetic operation of the numbers set, the elements to be described hereinafter will be provided so that their movements may be transmitted through a mechanism coupled to a motor through a linkage in a manner as will be described in more detail hereinafter. The above elements are comprised of 11 vertically disposed main racks 16 whose heel portions 17 are disposed in opposed relation with the pins 10 and 11 respectively and which have slots 18 into which is fitted a guide shaft 19.

A comb-shaped guide plate 20, into which are fitted the heels 17, is vertically disposed in parallel with the main racks 16. Each decimal carry pawl 22 is supported and guided in substantially perpendicular relation with the main rack group 16 by a decimal carry auxiliary lever 29 supported by a decimal carry pawl shaft 28 and a decimal carry pawl shaft 21. Each decimal carry pawl 22 has a stepped portion 23 upon which is supported a decimal carry pin 24 fixed to the main rack 16 and has a heel 25 extended toward the lateral side surface of the tooth 26 of the main rack 16. At the rear end portion of the decimal carry pawl 22 is formed a slot 27. Within the slots 18 of the main racks 16 are extending the decimal carry pawl shaft 28 trans-

versely at a right angle relative to the main rack 16. To the decimal carry pawl auxiliary lever 29, rotatably carried by the decimal carry pawl shaft 21 is rotatably fixed the heel through the auxiliary lever attachment pin 30. The decimal carry pawl 22 is guided forwardly and backwardly by the decimal carry pawl shaft 21 and the decimal carry pawl auxiliary lever 29. At the rear end portion of the decimal carry pawl 22 are formed a heel 31 and a returning heel or leg 32. The decimal carry pawl 22 is further guided by a decimal carry pawl resetter 35 pivoted by a pivot 33 in addition to the above described decimal carry pawl auxiliary lever 29 and the decimal carry pawl shaft 21. The decimal carry pawl resetter 35 has a depending finger 36. The main rack 16 has a slot 37 into which is fitted a type bar attachment pin 39 fixed to a type bar 38. The main rack 16 is permitted to move vertically by a distance determined by the length of the slot 37. The type bar 38 and the main rack 16 are interconnected through a spring 40 and the main rack 16 is normally biased downwardly. The types from digits 1 to 9 are disposed vertically upon the head of the type bar 38 and in opposed relation with the platen 41. A slot 42 is formed in the type bar 38 in parallel with the above digit types and the type bar 38 is displaced toward the paper 43 around the platen 41 so that a number set or calculated may be printed upon the paper 43, as will be described in more detail hereinafter. Type bar 38 is raised by a type bar spring 44.

A pair of accumulator pinions 45 and 46 are rotatably carried in front of each main rack 16 by pinion shafts 47 and 48, respectively, which in turn are secured to the pinion holder 49. The pinion holder 49 is rotatably carried by a pinion holder shaft 50 which is secured to the accumulator holder 51. Either of the accumulator pinions 45 and 46 may be moved toward their corresponding main rack 16 through a suitable cam mechanism for engagement with the teeth 26 of the main rack 16.

Slots 52 are formed through both of the side plates and receive therein a transversely extending type bar release shaft 53 whose vertical movement may be controlled by the lever mechanism and linkage coupled to the motor 54, as will be described in more detail hereinafter, so that upon vertically upward movement of the type release shaft 53, the main rack 16 is caused to move upwardly.

The decimal carry mechanism, shown in FIGS. 1 to 4, includes the decimal carry pawls 22, each of which slides while guided by the decimal carry pawl auxiliary lever 29 and the decimal carry pawl shaft 21. Upon the stepped portion 23 of the decimal carry pawl 22 rides the decimal carry pin 24 which drops to the lower side of the stepped portion 23 when the decimal carry pawl 22 is retracted so that the main rack 16 is caused to move downwardly by a distance corresponding to the height of the stepped portion 23. The main rack 16 is previously maintained in its raised position when the decimal carry pawl 22 is advanced, as will be described in more detail hereinafter, and the decimal carry pawl 24 rests upon the upper side of the stepped portion 23. The above described height of the stepped portion 23 corresponds to one pitch of both of the accumulator pinions 45 and 46. When the pinions 45 and 46 are meshed with the teeth 26, the decimal carry pawl 22 is

caused to retract by them because they have the cams 45a and 46a, respectively, disposed along one side of the teeth thereof, respectively as best shown in FIG. 5c.

Next, the addition, subtraction and the decimal carry mechanism will be described with reference to FIGS. 1 to 5. The digits of a number or numbers to be operated may be set up by depressing the corresponding key tops 3 and 3a, so that the pins 10 and 11 are caused to move backwardly through the digits levers 7 and 7a, while the pin box 8 is shifted to left (in FIG. 2) by a distance corresponding to the number of digits set up. Upon depression of an operation key top, described in more detail hereinafter, the number is set up or arithmetic operation may be executed while the motor 54 is driven, so that a main shaft 59 as well as a cam 194 may be rotated through gears 55, 56, 57 and 58. The type bar release shaft 53 is caused to move upwardly through the first half rotation of the cam 194, so that the type bar 38 is released and moved upwardly by the type bar spring 44. Thus, the type bar attachment pin 39 is caused to abut against the upper side edge of the slot 37, so that the main rack 16 is caused to move upwardly also. The upward movement of the main rack 16 may be limited by either of the pins 10 or 11 which extends into the path of the heel 17. Therefore, it will be noted that the main rack 16 stops at a position corresponding to a digit set up by the key top 3 or 3a. The type bar 38 is also stopped, when the main rack 16 is stopped so that the type corresponding to said digit may be aligned with the central circumference of the platen 41, whereby said digit may be printed upon the paper 43 supplied from the spool 61 in such a manner, as described in more detail hereinafter.

Upon next half rotation of a latch holder 60, the type bar 38 is caused to move downwardly again. In this case, at the initiation of this downward movement, either of the accumulator pinions 45 or 46 is made in mesh with the teeth 26 of the main rack 16 and is rotated through the downward movement of the main rack 16 caused by the downward movement of the type bar release shaft 53. Thereafter, the main rack 16 returns to its initial or normal position. That is, the main rack 16 slides by a distance corresponding to the digit set up by the pin 10 or 11. The accumulator pinion 45 or 46 is caused to rotate through an angle corresponding to said displacement of the main rack 16, that is the number of teeth thereof, which in turn corresponds to the above set digit.

In the similar manner as described above, the digits of the number may be sequentially set as the key tops 3 or 3a are depressed and the motor is driven.

When the accumulator pinions 45 and 46 are caused to make one complete rotation by two subsequent operations, the cam 45a or 46a of the accumulator pinion 45 or 46 abuts against the heel 25 of the decimal carry pawl 22 of the next higher digit, thereby retracting the decimal carry pawl 22. Therefore, the decimal carry pin 24 which has been resting upon the upper side of the stepped portion 23 of the decimal carry pawl 22 is caused to drop to the lower side of the stepped portion 23 so that the main rack 16 is released from the decimal carry pin 22, whereby the main rack 16 is caused to move downwardly by the spring 40. The distance of this downward movement of the main rack 16 is such that the accumulator pinion 45 or 46 in mesh

with the main rack 16 may be caused to rotate through an angle corresponding to one tooth thereof. Thus, one carry may be accomplished. It is to be noted that in case of addition, the accumulator pinion 45 is made to be in mesh with the rack 16 while in case of the subtraction, the accumulator pinion 46 is made to be in mesh with the teeth 26 of the main rack 16. To obtain the sum of the numbers set as described above, the (minus) T key top 62 is depressed.

Referring to FIGS. 3 and 6A, 6B1, 6B2, 6B3 and 6B4, upon depression of the -T key top 62, the -T key stem 63 is caused to slide in its longitudinal direction so as to push the inclined surface 64a of a -T engagement control plate 64, so that the plate 64 may be moved toward a locating fork 65.

The heel or leg 64b of the control plate 64 engages with a second tooth 65b of the locating fork 65 so that the fork 65 is caused to move to the right by a distance corresponding to one half of the displacement of the pin box 8 upon the guide shaft 9. The free end of one arm of the locating fork 65 is bifurcated as shown at 66 so as to engage with a grooved cam shaft 67, thereby actuating a grooved cam follower 68, as shown in FIG. 6A. The locating fork is coupled to the grooved cam follower 68 through a spring (not shown), so that upon depression of the -T key top 62 the grooved cam follower 68 is also caused to move to right, so that its arm 68a engages with cam portion 70 of a cam 69 carried integrally by a main shaft 59. The arm 68b of the grooved cam follower 68 is moved to the right and engages with the cam portion 71 of the cam 69. A grooved cam 72 carried by the grooved cam shaft 67 rotates in unison with the grooved cam follower 68. The grooved cam 72 has a cam slot 73 into which is fitted an accumulator drive pin 74 integrally secured to the accumulator pinion holder 49 of the pinions 45 and 46. Upon rocking motion of the grooved cam 72, the accumulator holder 49 is caused to move in the longitudinal direction of the grooved cam 72, so that the accumulator pinions 45 and 46 may be moved toward the teeth 26 of the main rack 16, thereby engaging either of them with the teeth 26 or disengaging therefrom.

Upon depression of the -T key top 62, a switch 77 is closed through a motor release connector 75 (see FIGS. 7A and 7D) and a switch release lever 76, so that the motor driving circuit (FIG. 7A) is closed. Upon rotation of the motor 54, the main shaft 59 is caused to rotate through the gears 55, 56, 57 and 58, so that through a well known mechanism the type bar release shaft 53 is caused to move upwardly, as shown in FIG. 4, whereby the main rack 16 is caused to move upwardly by a distance slightly in excess of one tooth of the main rack 16. Therefore, a credit balance bridge 34 is caused to rotate about the shaft 33, so that the heel or leg 34a of the credit balance bridge 34 is moved downwardly out of the path of the decimal carry pawl 22, thereby the decimal carry pawl 22 is returned to its non-operative position by the decimal carry pawl resetter 35. In this case, the decimal carry pin 24 rests upon the upper side of the stepped portion 22 of the decimal carry pawl 23, that is, the pin 24 returns to its initial position.

The decimal carry pawl 22 may be retained in either of said two positions by means of a spring 78.

After said slight upward movement of the main rack 16, it starts the downward movement and immediately after the decimal carry pin 24 has contacted with the upper side of the stepped portion 23, the grooved cam 72 is caused to rock by the actuation of the arm 68b which in turn is actuated by the cam portion 71, so that either of the accumulator pinions 45 or 46 is made to be in mesh with the teeth 26 of the main rack 16 through the accumulator drive pin 74 fitted into the cam slot 73. Thereafter, the main rack 16 moves upwardly again thereby rotating either of the accumulator pinions 45 or 46 and this rotation is stopped when either of the cams 45a or 45b abuts against the lower portion of the heel or leg 25 of the decimal carry pawl 22, thereby stopping the upward movement of the main rack 16.

Thereafter, the hammer 79 drives the type bar toward the platen 41 through the finger 80 and the slot 42, thereby accomplishing the printing, and the accumulator pinion is released from the main rack 16 through the grooved cam 72 which is not caused to rock in the reversed direction through the cam portion 71 and the arm 68, as described in more detail hereinafter. To sum up, upon rotation of the accumulator pinions 45 and 46, the main rack 16 is displaced by a distance corresponding to the angle of rotation of the pinions, so that the type bar 38 and a series of types fixed thereto which is resiliently coupled to the main rack 16 is displaced accordingly to a position corresponding to the digit positioned or indicated by the pinions thereby printing the digit upon the paper 43. The sub-total operation is carried out in a manner similar to that described above. In this case, a +S key top 82 is depressed, so as to control the +S key stem 81 whose construction and function are similar to those of the -T key stem 63 described hereinabove, but the -T engagement control plate 64 remains stationary, so that all of the components drivingly coupled thereto remain also stationary. It must be noted especially that the arm 68a is not actuated by the cam portion 70. Therefore, the above described operation is cycled in the case of addition while the accumulator pinion 45 or 46 remains in mesh with the teeth 26 of the rack 16, thereby remaining in the position corresponding to the sub-total value or number. So far, the grand total and sub-total additions have been described with the positive numbers, but it should be understood that the present invention enables the addition of the negative numbers in a manner similar to that described above. That is, even when the absolute value of a negative number is greater than that of a positive number, the arithmetic operation may be carried out.

A "negative addition operation" may be required when the subtrahend is greater than the total of the numbers so far added together. In this case, a number may be set in a similar manner as in the case of a positive number. However, instead of the +S key top 82, the key top 62 identical to the -T top key may be depressed. The subsequent operation is similar to that described hereinabove. That is, the control plate 64 is moved so that the heel or leg 64b thereof abuts against the sloping surface 65a' of the first tooth 65a. In this case, since the pin box 8 is moved the left upon setting a number, the locating fork 65 has already been displaced to the left by one step by means of a spring (not

shown). Upon abutment of the heel or leg 64b against the sloping surface 65a', the locating fork 65 is displaced to the right by a distance corresponding to one half of one tooth so that the arm 83, see FIG. 8, on the left side of the locating fork 65 is caused to displace toward the left, thereby releasing an engagement indicator plate 85 fitted into a slot 84 from the fixed teeth (not shown) upon the base plate 1, as shown in FIGS. 8 and 9. The other end of the indicator plate 85 is coupled through a pivot 86 to an accumulator control lever 87 which is rotatably fixed to a control level shaft 88. Upon depression of the -T key top 62, the motor 54 is driven in the similar manner, as described above, so that an engagement direction dictating cam 90 is driven by the main shaft 59. The engagement direction indicating cam 90 actuates the accumulator control lever 87 through a roller 91. The initial position of the accumulator lever 87 is shown in FIG. 9B. When the engagement direction indicating cam 90 rotates through some angle, the accumulator control lever 87 is caused to rotate in the counterclockwise direction in FIG. 9 to a position indicated in FIG. 9C. Upon rotation in the counterclockwise direction of the lever 87, the right end portion 87 thereof is caused to move upwardly, so that an accumulator settle arm 92 made integral with the accumulator pinion holder shaft 50 is caused to rotate in the clockwise direction in FIGS. 9A, and 9B, so that the pinion holder is also rotated, thereby engaging the accumulator pinion 46 with the teeth 26 of the main rack. The subsequent operations are similar to those of addition.

When the absolute value of a negative number is larger than that of a positive number and when it is desired to obtain the negative total or sum after a series of operations, the operation similar to the addition of the positive numbers described above is, cycled. That is without setting a number upon the keyboard, the -T key top 62 is depressed.

In the course of subtraction, the decimal carry pawl 22 is retracted by the cam 46a of the accumulator pinion 46, so that the heel or leg 22a of the decimal carry pawl 22 causes the heel or leg 34a of the credit balance bridge 34 carried by the reset shaft 33 to be released. Thus, the credit balance bridge 34 is caused to rotate by a spring (not shown) carried by a credit balance pusher 93 made integral with the credit balance bridge 34 through a coupling 34b of the credit balance bridge 34. In this case, by the same spring, the credit balance pusher 93 is displaced forwardly. Since the accumulator pinion 46 is in mesh with the rack 16, the pin 98 of the accumulator settle arm 92 fixed to the pinion holder shaft 50 is not in engagement with the credit balance pusher instruction plate 96, so that the pusher is rotated by the spring upwardly about the credit balance bridge coupling 34b. Thus, the lower end 94a of the credit balance stopper 94 is caused to rotate backwardly by the upper surface 93b, so that the engagement instruction plate 85 is released.

To sum up, upon depression of the -T key top 62, the main shaft 59 rotates, thereby rotating the engagement direction indicating cam 90, moving the accumulator control lever 87 downwardly, rocking the accumulator A upwardly, as described above, and engaging the accumulator pinion 46 with the main rack 16. During the above operation, the following operations will

be performed in the same sequence as described in case of the addition of the positive numbers. The same is true for obtaining the sub-total of the negative numbers.

When the sum passes zero and becomes a negative value in a well known manner, the decimal carry pawl 22 of the most significant digit (the leftmost) causes the decimal carry pawl 22 of the least significant digit (the rightmost) to displace backwardly through the heel or leg 34a made integral with the credit balance bridge 34. Next, and as described hereinbefore, the credit balance bridge 34 is caused to return to its inoperative position by a stud (not shown) made integral with the hammer cam 99 which is rotated by the main shaft 59.

The machine according to the present invention is provided with a mechanism for printing the signs corresponding to the operations performed upon a paper fed from a rolled paper.

This mechanism comprises a sign support plate 100, FIG. 6A, FIG. 10A in engagement with the slot 65c of the locating fork 65. The first stepped portion a of the sign indicator plate 100 is adapted to engage with a stepped finger 102 formed integral with a sign rack 101 disposed at the right of the rows of the main racks 16. The sign rack 101 is coupled to a sign type bar 103 through the pin 39 and the sign type bar 103 carries the types corresponding to the signs of operations. As described hereinabove, the locating fork 65 is displaced by a spring 105 in the axial direction thereof upon depression of the key top 3, so that the sign indicator plate 100 is displaced to left whereby the stepped portion a is positioned upwardly of the first stepped portion of the stepped finger 102 and the sign rack is locked in its inoperative position. In this case, the sign type bar 103 is not permitted to move upwardly, so that no sign is printed upon the paper 43. This means that the addition or subtraction is being carried out. However, in case of subtraction, the negative sign may be printed upon the paper 43 by a separate mechanism of well known type (not shown). In case of the sub-total or intermediate sum, upon depression of the +S key top 82, the sign indicator plate 100 will not be displaced as described with reference to the locating fork 65, but the first stepped portion a is engaged with the second stepped portion y of the finger 102 which is formed below the first stepped portion x.

The vertical spacing between the first and second stepped portions x and y corresponds to three types, so that the sign rack 101 is caused to move upwardly by a distance of three types of the sign type bar 103 for sub-total or intermediate sum sign so as to print it upon the paper 43.

Upon depression of the -T key top 62, the locating fork 65 is displaced to the right together with the sign indicator plate 100 and the first stepped portion a of the sign indicator plate 100 is moved above the third stepped portion z of the stepped finger 102. The third stepped portion z is the lowermost position, so that the sign rack 101 is caused to move upwardly by a distance corresponding to four types, thereby printing the sum sign upon the paper.

According to the machine or the present invention, continuous addition may be effected by the addition mechanism of the type described above. That is, a repeat key 106 is set to the left so that a repeat lever 107

is also set to the left thereby displacing to the left a clear stopper 108 coupled to the lever 107 so as to engage with a clear lever 109. Thus, the clear lever 109 is displaced outwardly. Next either the +S key top 82 or the -T key top 62 is depressed for the operations as described hereinabove. Then, the clear lever 109, FIG. 15E, is displaced outwardly so that a clear cam 110 carried by the main shaft 59 causes a clear cam follower 111 to rock through a roller 112 carried by the clear cam follower 111. When the clear lever 109 in engagement with the clear cam follower 111 is displaced, the pin box 8 is prevented from returning to its inoperative position by means of a pin box drive arm 113, FIG. 15A. When the pin box 8 is not in its inoperative position, the same number may be printed and calculated without setting a new number upon the keyboard 2.

FIGS. 10A to 10E show a printing type selection device for selecting a zero to be set prior to or subsequent to a number, so as to permit a plurality of zeros to be set after the number, and a sign may be printed upon the paper 43 by the type bar 38. As described above, when both the main rack 16 and the type bar 38 reach their upward stroke ends by the type bar spring 44, so as to be positioned to the positions corresponding to the digits of a number to be set by the pins 10 and/or 11, the selection of zeros will be effected. In this case, the shaft 59 is rotated through some angle thereby driving the hammer cam 99 in such a manner that the recess 99a formed therein may be engaged with a hammer release roller 116 attached to one end portion of a hammer release bridge 115 pivotably fixed to a hammer release shaft 114. At the other end of the hammer release bridge 115 are pivotably fixed two parallel hammer release plates (right and left) 117 and 118 while the other ends of the hammer release plates 117 and 118 are coupled by a hammer release shaft 119. A hammer stopper 120 is pivotably carried by a hammer stopper shaft 121 for each main rack 16 in such a manner that each hammer stopper 120 is disposed adjacent to the horizontally disposed hammer 79. Each hammer stopper 120 has an arm 120a and a finger 120b extending to left so as to abut against the top of the corresponding finger 79a of the left adjacent hammer 79. When the fingers 120b are formed and arranged in the manner described above, the hammer stoppers on the right side thereof may be prevented from being lowered, but the hammer stops 120 on the left may be lowered. Another arm 120c of the hammer stopper has a heel or leg 120d which is located in front of and out of the passage of the teeth 26 of the main rack 16 when the hammer stopper is in its inoperative position. By means of a heel or leg 120e of the hammer stopper 120, it is maintained in its raised inoperative position to which is actuated by the hammer release shaft 119.

The hammer 79 has a finger 79a and a heel or leg 79b in addition to the above described finger 80 and one end of a spring (not shown) is fixed to the heel or leg 79b while the other end thereof is fixed to the finger 120f of the hammer stopper 120. Upon rotation of the main shaft 59, the recess 99a thereof causes the hammer release roller 116 to move downwardly, so that the hammer release bridge 115 is caused to rotate by the spring. The right hammer release plate 117 is caused to displace backwardly and at the initiation of

this displacement, the hammer 79 locked by the hammer release shaft 119 is released while the hammer stopper 120 locked by the hammer stopper heel or leg 120e is also released. Upon downward movement of the hammer stopper 120, the heel or leg 120d tends to engage with the teeth 26. That is, the leg 120d is extended into the passage of the teeth 26 only when no number is set to the main racks 16. On the other hand, when a number is set to the main racks 16, the heel or leg 120d engages with the crest of the tooth 26 of the main rack 16, so that the hammer stopper 120 moves upwardly and remains in this raised position. The finger 117a of the right hammer release plate 117 abuts against a heel 122a of a hammer bridge 122, so that the hammer bridge 122 is raised from the notch 79c of the hammer 79, thereby freely moving the hammer 79 by the spring whereby the type bar 3 is actuated through the heel or leg 80 for printing. In this case, it is to be noted that only when the hammer stopper 120 is in its raised position, the hammer 79 is ready for printing because the heel or leg 120d stops at the crest of one tooth of the teeth 126 of the main rack 16 to which is set a digit of a number.

On the other hand, the main racks 16 corresponding to the hammer stoppers 120 which move downwardly are not set with any digit, so that the motion of the hammer 79 is stopped by the finger 120b, thereby preventing the printing operation. Thus, the zeros not set may be selected and the digits already set are printed.

The addition and subtraction mechanism as well as the printing mechanism have been hereinbefore described and the multiplication and division mechanism are hereinafter described in the sequence of the operations.

MULTIPLICATION MECHANISM

First, the digits are set to the pins 10 and 11 of the pin box 8 by depression of the top keys 3 as in the case of addition and subtraction.

Next, the X key top 123 is depressed so that the X key stem 124 is lowered (See FIG. 3) and the following operations may be carried out:

1. When the end 125a of a non-addition plate lift lever 125 is pushed, a non-addition plate lift lever 127 secured to the lever 125 and a pin 126 are caused to rotate in the counterclockwise direction about a shaft 128, so that the end 127a of the lift lever 127 moves the non-addition plate 129 upward (see FIG. 11). The notch 129a of the non-addition plate pushes the arm 68c of the grooved cam follower 68, so that the end 68b of the grooved cam follower 68 may be moved to left, in order not to engage with the cam 69. By this operation, no number is set in the accumulator A (see FIG. 6).

2. When a sign-auto-total indicator lever 131 is caused to rotate by a pin 130 attached to the X key stem 124 in the counterclockwise direction about the shaft 128, the leading end 131a of the sign-auto-total indicating lever 131 (see FIG. 11) pushes a sign indicating plate shaft 132, so that the sign indicating disk 100 is caused to rotate in the clockwise direction about a clear plate shaft 133. Thus, the second stepped portion b of the sign indicating disk 100 is displaced to such a position where it may engage with the first stepped portion x of the stepped finger 102 attached to the sign rack 101 when the rack 101 is moved to its raised position.

Therefore, when the sign rack 101 is raised, the $\times$ type attached to the sign type bar 103 pivoted by the pin 39 to the sign rack 101 is ready for printing (see FIG. 6A, FIG. 8 and FIG. 10A).

3. The bent portion 124a of an $\times$ key stem 124 engages with the bent portion 134a of an $\times$ key lever 134, so as to move the $\times$ key lever to left, so that the projection 134b of the $\times$ key lever 134 is positioned below an = key stem 135 thereby preventing the depression of the key 136. When a cam follower set lever 137, whose one end is fitted into a bore 134c formed at the left end of the $\times$ key lever 134, is rotated in the clockwise direction about a portion 137a a portion fitted into the left outer side plate 138 not shown (see FIGS. 3 and 13), a caution pinion clear cam follower 139, in engagement with a bifurcated portion 137b of the cam follower set lever 137, is caused to slide to right along a guide shaft 141 attached to the hammer release shaft 114 and a rack holder 140, so that a bearing 143 attached to the cam follower 139 by means of a bearing holder 142 is moved to a position opposed to a caution pinion clear cam 144 carried by the main shaft 59 (see FIG. 12).

4. The motor release connector 77 is moved downwardly by the $\times$ key stem 124, so that the main shaft 59 is rotated. This operation is similar to addition and subtraction, so that no further description is provided.

In FIG. 12, upon rotation of the main shaft 59 in the counterclockwise direction, a releasing pin 145 for the engagement direction indicating cam 90 engages with the projection 146a of a caution pinion grooved cam 146, so that it is rotated in the clockwise direction. A driver pin which is fitted into the slot 146b of the cam 146 and is attached to a caution pinion drive arm 148 carried by a caution pinion holder shaft 147 causes the drive arm 148 to rotate in the counterclockwise direction about said caution pinion holder shaft. Then, a caution pinion holder 150 carried by the shaft 147 is moved, so that a caution pinion 152 carried by a caution pinion holder shaft 151, which also carries said caution pinion holder, is released from engagement with a sub-rack portion 153 of the main rack 16. Upon this disengagement, a settle spring 155 attached to a guide plate 154 engages with a caution pinion or quotient register 152, thereby preventing the rotation thereof. The quotient register or caution pinion comprises pinions. The above described operation is always carried out when one cycle is accomplished while the caution pinion 152 remains in engagement with the sub-rack 153 of the main rack 16 in every calculation (+, -, $\times$, =, Q).

Thereafter, the bearing 143 attached to the caution pinion clear cam follower 139 by the bearing holder 142 is moved by the caution pinion clear cam 144, carried by the main shaft 59, the cam follower 139 and the rack holder 140, which engages with the cam follower 139 through the hammer release shaft 114 and the guide shaft 141, are rotated in the counterclockwise direction, so that a rack 157 attached to the rack holder 140 by a pin 156 is caused to move upwardly and a drive pinion 158, which engages with the rack 157, is rotated in the counterclockwise direction. Since the drive pinion 158 is carried by the shaft 151 of the caution pinion 152, the shaft 151 is also rotated. Upon rotation of a zero resetting pawl 159 fitted into the

groove 151a of the shaft 151, the projection 159a of the zero resetting pawl 159 engages with the projection 152a of the caution pinion 152, so that the pinion 152 is rotated (see FIGS. 13, 12, 13A). The caution pinion 152 rotates to a position until the projection 152b abuts against a shaft 160 attached to the caution pinion holder 150. This is the position of the caution pinion 152 representing zero.

Upon rotation of the caution pinion clear cam follower 139 about the shaft 114 in the counterclockwise direction, a pin attached to an auxiliary engaging lever 161 which has been stopped by the projection 139a of the cam follower 139 is released, so that the auxiliary engaging lever 161 is rotated by a spring 163 about the pin 164 in the clockwise direction until the projection 161a of the auxiliary engaging lever 161 abuts against a pin 165 attached to the caution pinion grooved cam 146.

During the above described operation, the type bar 38 and the main rack 16 are moved upwardly until the heel or leg 17 of the main rack 16 engages with the pin 10 or 11 of the pin box 8. Also the sign type bar 103 and the sign rack 101 are moved upwardly until the second stepped portion of the indicating plate 100 engages with the first stepped portion of the stepped finger.

Thereafter, the hammer is actuated so that the multiplicand and $\times$ sign are printed upon the paper 43 (see FIGS. 12 and 10).

Prior to the downward movement of the type bar 38 and the main rack 16, a pin 166 attached to the caution pinion clear cam 144 carried by the main shaft 59 engages with the auxiliary engaging lever 161 pivotably secured to the caution pinion grooved cam 146 by means of the pin 164, so that the caution pinion grooved cam 146 rotates about a shaft 167 in the counterclockwise direction. Therefore, the pin 149, attached to the caution pinion drive arm 148 carried by the shaft 147 and fitted into the slot 146b of the caution pinion grooved cam 146, causes the caution pinion drive arm 148 to rotate about the shaft 147 in the clockwise direction, so that the caution pinion 152 carried by the shaft 151 attached to the caution pinion holder 150 is placed in engagement with the sub-rack 153 of the main rack 16. Thereafter, the type bar 38 and the main rack 16 move downwardly and the caution pinion 152 is rotated in the clockwise direction through an angle corresponding to a number of digits set by the pin 10 or 11 of the pin box 8, so that the multiplicand is set in the caution pinion 152. In this case, because of the reason described in (1) above, the accumulator A is not in engagement with the main rack 16, so that no number is set into the accumulator A. Thereafter, the pins 10 and 11 of the pin box 8 are cleared and a release plate 168 is returned to its initial position while the $\times$ key top 123 is returned to its original position.

All the operations instituted by the depression of the $\times$ key are then accomplished.

Next, a multiplication mechanism is described. In brief, the multiplication mechanism is such that a multiplier is set in the pin box 8, and the multiplicand set on the caution pinions 152 are repeatedly added digit by digit from the least significant digit thereof. The sum is accumulated in the accumulator A and no printing

and printing paper feed are made during the operation. The first rotation of the main shaft 59 is for preparation of multiplication operation. Then, the shaft 59 rotates a number corresponding to the number set upon the caution pinions and the subsequent rotation accomplishes the multiplication. A multiplier is set by the pins 10 and 11 in the pin box 8 by depression of the digit key tops 3. Next, the = key top 136 is depressed, so that the = key stem 135 is moved downwardly. When the repeat key 106 is set, the lower end 135a of the = key stem 135 releases the projection 107a of the repeat key stem 107, so that the repeat key stem 107 is also released by a spring 169 (see FIG. 3).

1. (see FIGS. 3, 11 and 14)

Upon depression of the = key stem 135, the upper end 135b of the key stem 135 engages with the projection 170a of an = lever 170, so that the lever 170 rotates about the shaft 128 in the counterclockwise direction. A pin 171 attached to the lever 170 actuates such that

a. when the arm 127b of the multiplicand plate lift lever 127 is raised, the lever 127 is caused to rotate about the shaft 128 in the counterclockwise direction while when the multiplicand plate 129 is lifted by the leading edge 127a of the lever 127 (see FIG. 11), the bifurcated portion 129a engages with the arm 68c of the grooved cam follower 68, so as to move it to left, so that the arm 68c may not engage with the engaging cam 69 and the arm 68b of the grooved cam follower 68.

b. (see FIGS. 6A, 8 and 10)

The end 100d of the sign indicating plate is pushed upwardly by a pin 171 attached to the lever 170, so that the sign indicating plate 100 is caused to rotate about the shaft 133 in the clockwise direction, thereby positioning the third stepped portion c of the sign indicating plate 100 to a position at which it may engage with the first stepped portion x of the stepped finger 102 when the rack 101 is raised. Thus, the sign = may be printed upon the paper by the sign type bar 103 when the sign rack 101 is raised.

c. (see FIGS. 11 and 15)

An arm 173, pivotably secured by a pin 172 to the lever 170, is caused to move by the rotation of the lever 170, so that a disk 175, rotatably secured to a guide plate 174, is caused to rotate in the clockwise direction, so that a continuous rotation slide plate 176 and a hammer stop slide plate 177 are released. The slide plate 176 is caused to move to left by a spring 178, so that the projection 176a of the slide plate 176 is moved to a position at which the projection 176a is opposed to the projection 181a of a release plate reset plate 181 attached to the release plate 168 by screws 179 and 180.

When the release plate 168 is caused to move to right (forwardly) by the spring 182, the projection 181a of the release plate reset plate 181 engages with the projection 176a of the slide plate 176, so that the release plate 181 is caused to rotate in the clockwise direction about the screw 179, so that the bent portion 181b of the release plate 181 may not engage with the reset cam 183 of the latch holder 60 secured to the main shaft 59.

Therefore, the release plate 168 is not reset, but remains rotated continuously during the operation. The slide plate 177 is caused to move to the left by a spring 185 until the bent portion 184a of the hammer stopper

184 engages with the projection 177a of the slide plate 177.

The above operation is carried out in order that the projection 177a of the slide plate 177 may be located below the bent portion 184a of the hammer stopper 184 upon upward movement of the hammer stopper 184 by the first rotation of the main shaft 59, thereby preventing the downward movement of the hammer stopper 184 and the printing operation during operation.

d. (see FIGS. 11 and 14)

Upon movement of an arm 186 rotatably secured to the lever 170 by the pin 172 due to the rotation of the lever 170, an arm 188, rotatably secured to the arm 186 by a pin 187, is caused to rotate in the clockwise direction about a pin 190, attached to an arithmetic operation set lever 189, so that a pin 191, attached to the arm 188, is opposed to the bent portion 129b of the non-addition plate 129 in the raised position, as described in (1)(a).

2. (See FIGS. 3, 11 and 14)

Upon downward movement of the = key stem 135, a pin 192 attached to the + key stem 135 causes the indicating lever 131 to rotate in the counterclockwise direction about the shaft 128, so that the leg 131b of the lever 131 causes an auto-total plate 193 to move backwardly. As will be described in more detail hereinafter, this is for positioning the locating fork to the sum position by the actuation of the auto-total plate 193 when the auto-total key is set, so that the sum may be rotated one more time after one rotation after the completion of the operation, so as to actuate the sum or total mechanism.

3. The downward movement of the motor release connector 77 by the = key stem 135 causes the main shaft 59 to be rotated continuously as described (1)(c).

During the first rotation of the main shaft 59, the type bar 38 and the main rack 16 move upwardly until the heel or leg 17 of the main rack 16 engages with the pin 10 or 11 of the pin box 8, while the sign type bar 103 and the sign rack 101 move upwardly until the third stepped portion c of the sign indicating plate 100 engages with the portion x of the stepped finger 102. Thereafter, the hammer mechanism is actuated, so that the multiplier and the = sign are printed, and then the type bar, the main rack and the sign type bar are moved downwardly. But as described in (1)(a), since the non-addition plate 129 is in its raised position, the rack 16 is lowered without engagement with the accumulator A. Consequently, no number is set in the accumulator A. Prior to the type bar 38 and the main rack 16 reaching their lowermost positions, the arm 188 and the non-addition plate 129, explained in (1)(d), are actuated, as will be described below, so that the next arithmetic operation may be carried out. Referring to FIGS. 14 and 16, upon rotation of the main shaft 59 in the clockwise direction, the arithmetic operation set cam 194a of a main cam 194, carried by the main shaft 59, rotates and engages with the right arm end 195a of a rocking lever 195, rotatably carried by the shaft 147, so that the rocking lever 195 is caused to rotate about the shaft 147. When the left arm end 195b engages with the bent portion 129c of the non-addition plate 129, and when the plate 192 is caused to rotate in the clockwise direction about the notch 196a of a hammer guide plate

40

45

50

55

60

65

196, the bent portion 129b of the non-addition plate 129 engages with the pin 191 attached to the arm 188, so that the arm 188 is caused to move to left. Therefore, the arithmetic operation set lever 189, rotatably secured by the pin 190 to the arm 188, rotates in the counterclockwise direction about the shaft 147, so that an arithmetic operation set plate 199, carried by an arithmetic operation set shaft 198, rotatably fixed to the right and left side plates, by means of the pin 197 fixed to the arithmetic operation lever 189, is caused to rotate in the clockwise direction about the shaft 198. In this case, the shaft 198 is also caused to rotate in the clockwise direction. Then, the operations, as described in (1) to (5) hereinafter, will be carried out. Simultaneously, the rocking lever 195 is rotated in the counterclockwise direction, so that the left arm end 195b of the rocking lever 195 engages with the bent portion 129c of the non-addition plate 129 thereby rotating it in the clockwise direction. Then, the bent portion 129d of the non-addition plate 129, raised by the end 127a of the non-addition plate lift lever 127, is released from the end 127a of the lift lever 127, so that the non-addition plate 129 is caused to move downwardly by a spring 200 and the notch 129a of the non-addition plate 129 engages with the arm 68c of the grooved cam follower 68. Therefore, the engaging cam 69 and the grooved cam follower 68, which have been locked in such a position that the cam 69 is prevented from engaging with the end 68b of the grooved cam follower 68, are released, so that the relation of the engaging cam 69 relative to the grooved cam follower 68 may become similar to the case of addition. Thus, from the next rotation the repeated additions may be carried out and the number may be set in the accumulator A. Upon rotation of the arithmetic operation set lever 189, the bent portion 189a thereof pushes the pawl 203a of a selector stop lever 203, rotatably carried by a shaft 202 attached to a selector 201, shown in FIG. 17, upward. The shaft 202 from a plate 204 (see FIG. 16C) attached to the machine frame 1, causes the selector stop lever 203 to rotate about the shaft 202 in the clockwise direction, thereby releasing the pawl 203a of the selector stop lever 203 from the plate 204 and setting the selector 201 free. Thus, the selector 201 rotates by a spring 205 until the leading end of the 201a of the selector 201 engages with the flanged portion 152c of the caution pinion 152 to which a digit of a number is set.

1. (see FIGS. 14 and 16)

Upon rotation of the arithmetic operation set plate 199 about the shaft 198 in the clockwise direction, a zero setting connecting plate 207 having an elongated slot 207a, into which is fitted the outer portion 206a of a pin 206 attached to the arithmetic operation set plate 199, is moved to right. Since the connecting plate 207 is interconnected with a zero setting plate 208 through a pin 209 attached to the zero setting plate 208 and fitted into a bore 207b formed at the left end of the connecting plate 207, the zero setting plate 208 is also moved to the right, so that the zero pins 12 of the digits less than the least significant digit of the multiplier may be set in the pin box 8. Therefore, the carry mechanism, which is actuated when a number is set into the pin box 8, is released, so that the box 8 becomes free. Since the repeated additions are carried

out from the least significant digit, and the added number is set in the accumulator A, when the carry is made, the zeros are set in the digits lower than the least significant digit of a number set.

2. (see FIGS. 14 and 18)

A caution pinion drive release plate 211 is placed in contact with the inter portion 206b of the pin attached to the arithmetic operation set plate 199 by a spring 210. Upon rotation of the arithmetic operation set plate 199 in the clockwise direction, the release plate 211 tends to move under the action of the spring 210, but will not be permitted to move, because the projection 212a of a caution pinion drive plate 212k fits into a square hole 211a of the drive release plate 211. However, by the downward movement of the type bar release shaft 53, the projection 212a of the drive plate 212 is released from the square hole 211a of the release plate 211, so that the release plate 211 is moved to right by the spring 210. When the type bar release shaft 53 is moved upwardly in the subsequent arithmetic rotations, the drive plate 212 may be moved upwardly until the grooved cam shaft 67 contacts with the lower side edge 212b of the square hole of the drive plate 212 by a spring 213. This is for rotating the caution pinion 152 by one tooth as the main shaft 59 makes one rotation. This mechanism is described in more detail hereinafter.

3. (see FIGS. 14, 16 and 19)

Upon rotation of the shaft 198 in the clockwise direction, a carriage set drive arm 214 carried by the shaft 198 rotates.

a. (see FIGS. 17 and 19)

The projections 215a of a carriage 215 receive the respective bushings 216 of the pin box 8. A carriage holding plate 217, secured to the pin box 8, is fitted into a square hole 218a of a carriage holding plate 218 secured to the carriage 215. A carriage set drive arm 214 engages with the leading edge 215b of the carriage, coupled to the pin box 8 through a spring 219 and a spring hook 220. When the carriage drive arm 214 rotates in the clockwise direction in FIG. 14, the carriage 215 rotates in the counterclockwise direction about the pin box guide shaft 9, so that the leg 201b of the selector 201 fits into the square hole 215c of the carriage, as shown in FIG. 17, thereby interconnecting the carriage with the selector 201 and the pin box 8. As described above, the carry may be effected by the actuation of the selector 201 due to the instruction from the caution pinion 152.

b. Upon rotation of the carriage set drive arm 214, the arm 214a of the drive arm 214 moves the hammer stopper 184 against a spring 221 along the shaft 167 and the arithmetic operation set shaft 198. Then, as described above, the bent portion 177a of the hammer stop drive plate 177 is in contact with the bent portion 184a of the hammer stopper 184, but upon upward movement of the hammer stopper, their engagement is released, so that the slide plate is located below the bent portion of the hammer stopper 184 by the spring 185, as shown in FIG. 15. In the subsequent rotation, the end 184b of the hammer stopper 184 (see FIGS. 10 and 17) engages with the hammer release bridge 115 so that the hammer release bridge 115 remains inoperative and no printing is made.

c. Referring to FIG. 17, upon rotation of the carriage set drive arm 214, the projection 223a of a slide plate 223 made in contact with the side surface of the drive arm 214 by a spring 222, is released from the drive arm 214 and moved by the spring 222, so as to be located below the drive arm 214 and the bent portion 129d of the multiplicand plate is released from the leading and 127a of the multiplicand lift lever 127, so that the reverse rotation of the drive arm 214 is not permitted even by the rotation of the drive arm 214, thereby preventing the rotation of the arithmetic operation set shaft 198 and setting it in position.

4. Upon rotation of the arithmetic operation set shaft 198 in the clockwise direction in FIG. 14, an engagement direction indicating plate release arm 224, carried by the shaft 198, is rotated in the counterclockwise direction in FIG. 13, so that an engaging indicating plate 225, arranged so as to be rotatable about the axis of holes 225a, is released from the engaging portion 224a of a release arm 224. But the engagement indicating plate 225 remains stationary, as in the case of addition and subtraction by the related operation of the division set slide plate (see FIG. 19) as described in more detail hereinafter. Therefore, a pin 229 attached to a caution pinion rotation direction instruction plate 228, and fitted into an elongated hole 227a of a caution pinion rotation direction instruction connecting plate 227, rotatably secured to the engagement instruction plate 225 by a pin 226, is rotated by the instruction plate 228 in the counterclockwise direction in FIG. 13 by a spring 230. Therefore, the pin 229 is in contact with the lower side edge 231a of an aperture or window formed through the right side plate 231. It is noted that the pin 229 of the instruction plate 228 is not contacted with the upper side of the elongated slot 227a of the connection plate 227. Therefore, as shown in FIG. 18B, the caution pinion 152 rotates in the direction in which the caution pinion 152 is set to zero in the subsequent operations, from the next rotation, as described in more detail, hereinafter.

5. (see FIGS. 14, 15 and 17)

Upon rotation of the arithmetic operation set shaft 198 in the clockwise direction, a pin box clear drive release arm 232, carried by the shaft 198, is caused to rotate, so that a connecting lever 234, pivoted by a pin 233 to the release arm 232, is caused to move to right. A pin 238 of a pin box clear drive release lever 237 pivotably secured by pin 236 (see FIG. 20) to a clear lever guide plate 235, is fitted in an elongated slot 234a of the connecting layer. Upon rotation of the release lever 237, about the pin 236 in the clockwise direction (see FIG. 20), an auxiliary pin box drive lever 241, which is rotatably pivoted to the clear lever 109 by a pin 239 and is rotated in the counterclockwise direction by means of a spring 240, so as to contact with the bent portion 237a of the release lever 237, is caused to rotate in the clockwise direction. Therefore,

a. The notch 109a of the clear lever 109 is released from engagement with a roller 242 attached to the pin box driven arm 113 even when the clear lever 109 is moved (this movement is such that one reciprocation is made for one rotation, as in the case of the pin box clear mechanism in addition and subtraction) so that no pin box clear is effected.

b. (see FIG. 20)

When the lever 241 is rotated in the clockwise direction and when the arithmetic operations are carried out in the pin box 8 from the least significant digit to the most significant digit, a hook 245 which is 5 rotatably secured to the auxiliary lever 241 by a pin 243, imparted to rotate the counterclockwise direction by a spring 244 and is held in position by the auxiliary lever 241 in engagement with the bent portion 245a of the hook 245, executes a reciprocal movement 10 together with the clear lever 109 and pulls a pin 248, attached to a lever 247 rotatably secured to the machine frame 1 by a pin 246, whereby the lever 247 is rotated in the clockwise direction about the pin 246. In 15 this case, when a sector gear 249 in engagement with the toothed portion 113a of the drive arm 113 is not permitted to rotate, because the pin box 8 is stopped by the caution pinion 152, when the lever 247 is rotated, the end portion 247a of the lever 247 which has been 20 pressed against the sector gear 249 by a twisted spring 250, is released from the sector gear 249, so that the force of the spring 250 causes the sector gear 249 to rotate in the clockwise direction about the pin 246. Therefore, the pin box drive arm 113 in engagement 25 with the sector gear 249 is caused to rotate in the counterclockwise direction thereby providing the force for moving the pin box for carry.

Because of the operations described in (1) to (5) above and because the release plate 168 is not reset, 30 the main shaft 59 is continuously rotated and the operations (repeated additions) are carried out.

Whenever the main shaft 59 makes one rotation, the type bar release shaft 53 makes one vertical reciprocal motion, so that when the caution pinion drive plate 212 is released, as described above in (2) (see FIGS. 18A, 35 18B and 21), so that the type bar release shaft 53 is moved upwardly, the drive plate 212 (see FIG. 18B) moves upwardly by the spring 213 until the grooved cam shaft 67 contacts with the lower side edge 212b of the square hole of the drive plate 212. Thereafter, the release shaft 53 moves downwardly, and the left and right pawls 253 and 254 are caused to move downwardly. The left and right pawls 253 and 254 are 40 rotatably secured to the drive plate 212 by the pin 251 in such a manner that under the action of a spring 252 the arms 253a and 254a are pressed against the grooved portion 228a of the caution pinion rotation direction instruction plate 228, as best shown in FIG. 45 21. Since the rotation direction instruction plate 228 is held in the position shown in FIG. 18B as described in (4) above, when the lower end of the left pawl 253 engages with a column member 257a of a four column assembly 257 carried by a shaft 256 having a key slot 50 256a and extending rotatably between the left and right side plates 255 and 231, the four column assembly 257 is caused to rotate together with the shaft 256 in the counterclockwise direction through an angle of 90°.

A pawl 260, having a projection 260a is engaged with 55 the notch 259a of a drive plate 259 securely fixed to the selector shaft 258, which extends between the left and right side plates 255 and 231 and also carries the selector 201. The pawl 260 is engaged with the groove 256a of the shaft 256, so that the pawl 260 is caused to rotate in clockwise direction through an angle of 90° together with the shaft 256, so that the projection 260b of the pawl 260 engages with the tooth 152d of the caution

pinion 152, so as to rotate the same by one tooth about the shaft 151 in clockwise direction. (see FIG. 18A). The caution pinion 152 is held in stationary position, because, as described hereinabove, the selector 201 has abutted against the flanged portion 152c of the caution pinion 152. Therefore, the digit set the caution pinion 152 is reset to zero. Thus, the repeated additions are carried out in this digit by a number corresponding to a number (multiplicand) set in the caution pinions 152 and when the caution pinion becomes zero at this digit, the end 201a of the selector 201 is opposed to the zero groove 152e of the caution pinion 152, so that it is released from the flanged portion 152c of the caution pinion 152. Thus, by the force of the pin box drive spring 261 (see FIG. 3), the spring 205 (see FIG. 13) and the spring 250 described in the (5) (b) above, the pin box 8, the selector 201, and the carriage 215 are coupled with each other, as described in (3) (a) above, so that the carry is effected until the end 201a of the selector 201 is stopped by the flanged portion 152c of the caution pinion 152 in the digit higher than the caution pinion which is rotated to its zero position. In this case, a detent plate 262, shown in FIG. 17, is carried by the arithmetic operation set shaft 198 for rotation in the clockwise direction by a spring (not shown) and is in engagement with a groove 215d formed at the bent portion 215b of the carriage 215, so that the carriage 215 is not permitted to return to left (the lower digit direction). When the carriage 215 is moved to the higher digit (to the right), the cam 262b (see FIG. 17C) of the detent plate 262 is caused to move upwardly by the shoulder of the groove 215d of the bent portion 215b of the carriage 215, so that the detent plate 262 is caused to rotate in the counterclockwise direction about the shaft 198, thereby releasing the stop 262a of the detent plate 262 from the groove 215d. When the carriage 215 is stopped in the next higher digit by the engagement of the selector 201 with the flanged portion 152c of the caution pinion 152, the stop 262a of the detent plate 262 is made to engage with the groove 215d of the carriage 215 by the spring, so that the carriage 215 may be securely held in position. As the multiplicand is repeatedly added from its least significant digit to the most significant digit, the multiplicand set in the caution pinions 152 is cleared to zero and the main shaft 59 rotates a number of rotations corresponding to the number set in the caution pinions 152. When all the digits of the caution pinions become zero, the pin box 8, the carriage 215 and the selector 201 are all moved to the most significant digit, so that the bent portion 215e of the carriage 215 abuts against the bent portion 223b of the slide plate 223, thereby moving the slide plate to the right (see FIG. 17). By the spring 263, the set shaft 198 is rotated in the clockwise direction so that the settings or operations described in (1) to (5) above are all cleared or stopped.

Next referring to FIGS. 11 and 15, the slide plate 176 and the slide 177 are not returned to their initial positions, so that the release plate 168 is not set by the slide plate 176 and the main shaft 59 rotates, while the hammer stopper 184 is not reset by the slide plate 177, so that there is no printing is made. Referring to FIGS. 17 and 22, when the pin box 8, the carriage 215 and the selector 201 are advanced to a higher digit, the bent portion 215f of the carriage 215 engages with a leg

265a of a type bar lifting stopper 265 which is interposed between the left and right side plates 255 and 231 for axial movement and is normally pressed against the right side plate 231 by a spring 264, so that the stopper 265 is moved toward the left side plate 255. Then, the leading end 265b of the stopper 265 is displaced to a position above a leg 266a of a connecting plate 266, so that when the type bar 38 is moved upwardly the release arm connecting plate 266 may not be permitted to move upwardly. In this case, as shown in FIG. 22B, a bound preventive lever 268 is secured rotatably to the machine frame 1 and is biased, so as to rotate in the direction indicated by the arrow (clockwise direction) by a spring 267 so that the end portion 268a of the lever 268 abuts against the side face 265c of the lifting stopper 265. The end portion 268a is positioned backwardly of the side face 265c, as shown in FIG. 22, so that the lifting stopper 265 is prevented from returning by the spring 264 while the bent portion 268b of the preventive lever 268 may engage with the locating fork 65. In the next rotation, the end 265b of the lifting stopper 265 engages with the leg 266a of the lifting arm 266, so that the type bar lifting shaft 53 is fitted into a hole of the lifting arm 266. Therefore, type bar 38 is not moved upwardly while the main shaft 59 rotates, and, as in the case of addition, the pin box 8 is returned for resetting for clearing the pins 10 and 11. In this case, the selector 201 is stopped, since the bent portion 215g of the carriage 215 engages with the leg 201b of the selector 201, so that the pin box 8 and the carriage 215 are returned and the pawl 203a of the selector stop lever 203, secured for rotation about the shaft 202 by a spring 269, engages with the plate 204, attached to the machine frame 1, as shown in FIG. 16.

When the selector 201 is started to return by the pin box 8 and the carriage 215, the leg 201b of the selector 201 engages with and returns the pawl 177b of the slide plate 177, as shown in FIG. 15A, so that the projection 176a of the slide plate 177, shown in FIG. 11, disengages from the leg 181a of the release plate reset plate 181. The reset plate 181 rotates in the counterclockwise direction about a screw 179 by a spring 270, is reset, and is returned by a cam 183 of the rack holder 60 carried by the main shaft 59, thereby completing the rotation. When the pin box 8 is reset, the locating fork, shown in FIG. 22A, is returned, so that the projection 268b of the bound preventive lever 268 is caused to rotate in the counterclockwise direction, thereby releasing the lifting stopper 265. Therefore, the lifting stopper 265 may be returned by the spring 264. All of the operations initiated by depression of the = key have then been accomplished. Since the sum of the arithmetic operations is set in the accumulator A, the sum mechanism will be actuated by the depression of the -T key top 62, as in the case of the sum operation of the addition.

Next, when the key 271 is set to the upper side in FIG. 3, the leading end 272a of the stem 272 of the A key 271 (see FIG. 15) pushes the leading end portion 176c of the slide plate 176, so that the leg 201b of the selector 201 engages with the pawl 176b of the slide plate 176. Therefore, when the pin box 8, the carriage 215 and the selector 201 are started to return in the last rotation of the above arithmetic operation, the slide

plate 176 is not reset, so that the release plate 168 is not reset by this last rotation, whereby the main shaft 59 may be continuously rotated. However, when the pin box 8, the carriage 215 and the selector 201 have been returned, the end 215h of the carriage 215 pushes the lower projection 176d of the slide plate 176, so that the release plate 168 may be reset and one more rotation is made. In this case, the locating fork 65 is returned by the pin box 8, the end 193a of the auto-total plate 193 described in (2) above (see FIG. 6) is moved upwardly by the sloping surface of the right pawl 65d, when the locating fork 65 is returned, since the leading end 193a of the auto-total plate 193 is pressed against the right pawl 65d of the locating fork 65 by a spring 273. Furthermore, when the locating fork 65 is returned, the leading end 193a of the auto-total plate 193 engages with the right pawl 65d of the fork 65 by the spring 273. This position of the locating fork 65 is similar to the total position in addition, so that an additional rotation causes operation of the total mechanism.

DIVISION MECHANISM

DIVIDEND INTRODUCTION MECHANISM

According to the dividend introduction mechanism of the present invention, the caution pinions are set to zeros in order to set a quotient. A dividend is printed on the paper 43 in the first rotation. The most significant digit of the dividend is shifted, so as to be set in the most significant digit position of the accumulator A. The dividend is set in the accumulator in the second rotation.

A number is set by depressing the corresponding key tops in the pin box 8 by pins 10 and 11. Next, the key top 274 is depressed, so that the key stem 275 is moved down and the following operations occur.

1. As in the case of the $\times$ key operation described in (1) of multiplication, the non-addition plate lift lever 125 is pushed, so that no number is set in the accumulator A in the first rotation.

2. Referring to FIGS. 23 and 24, the key stem 275 engages with the projection 280a of a continuous rotation instruction plate 280, carried by a dividend introduction bridge 278, via a screw 279, which in turn is rotatably interposed between a guide pin (not shown) of the right side plate 276 and a guide pin 277 attached to the left side plate 138, so that the bridge 278 is rotated in the counterclockwise direction through an angle corresponding to the displacement of the projection 280a pushed by the key stem 275. Then, a set plate 282, which is rotatably secured to a pin 281 attached to the left plate 278a of the bridge 278, and whose leading curved portion 282a is guided by a boss 283a of a dividend set cam 283, carried by the main shaft 59, tends to rotate in the clockwise direction, as the leading curved portion 282a is released from the boss 283a. In this case, the upper curved portion 282b of the set plate 282 tends to contact with the boss 283a. However, a cam follower 286 is rotatably carried by the shaft 114 and has a bearing 284 pressed against the cam 283 by a spring 285 and a pin 287 fixed to the leading end of the cam follower 286. The leading tip end 282c of the set plate 282 abuts against the pin 287, so that the set plate 282 cannot rotate in the clockwise

direction, whereby the upper curved portion 282b of the set plate 282 cannot contact with the boss 283a. Upon rotation of the main shaft 59, however, the divident set cam 283 is rotated in the clockwise direction and the cam follower 286 also rotates in the clockwise direction, so that the pin 287 is disengaged from the end 282c and the set plate 282 rotates further, thereby contacting the upper curved portion 282b with the boss 283a of the cam 283. In this case, the pin 287 of the cam follower 286 engages with the leading end 282d of the set plate 282.

3. Upon depression of the key stem 275, the motor release connector 75 is moved downwardly, so that the main shaft 59 is rotated. This operation is similar to that of addition.

After the operations described in (1), (2) and (3), and upon rotation of the main shaft 59, as shown in FIGS. 10A, 10D and 10E, the main rack 16 and the type bar 38 are moved upwardly until they engage with the pins 10 and 11, set in the pin box 8, while the sign rack 101 moves upwardly until the first stepped portion x of the stepped finger 102 of the sign rack 101 engages with the first stepped portion a of the indicating plate 100, that is, up to the type of the sign type bar 103, since the sign indicating plate 100 is not moved. This position is similar to that in addition and subtraction. Then, the printing is accomplished. In this case, the leading end 288a of the sign hammer stopper 288, in opposed relation to the sign rack 101, rotates in the counterclockwise direction, but since the non-addition plate 129 is in its raised or lifted position, the pin 289 of the hammer sign stopper 288 abuts against the left end 129e of the non-addition plate 129, so that the rotation is stopped, whereby the hammer 79 is not stopped by the projection 288b of the sign hammer stopper 288. Therefore, the sign type bar 103 prints mark upon the paper. In addition and subtraction, the non-addition plate is not lifted, so that the sign hammer stopper 288 engages with the ridge portion 101a of the sign rack, thereby rotating in the counterclockwise direction, so that the hammer 79 is stopped by the projection 288b of the sign hammer stopper 288. Therefore, nothing is printed upon the paper.

The above is similar to the zero selecting mechanism in addition and subtraction. A number set by the type bar 38 and the sign set by the sign type bar 103 are printed upon the paper and thereafter the type bar 38 and the sign type bar 103 are returned to their lowermost positions. Prior to these movements, the non-addition plate 129 is lowered by the cam 194a of the main cam 194 carried by the main shaft 59 as in the case of the = key operation. Therefore, in the next rotation, the addition is carried out.

Referring back to FIG. 24, because of the operations described in (2) above, after the type bar 38 has been lowered, the dividend set cam 283 (see FIG. 24), carried by the main shaft 59, causes the cam follower 286 to rotate in the counterclockwise direction, so that the set plate 282 whose leading end portion 282d is in engagement with the pin 287 of the cam follower 286, is further moved to right. Therefore, the bridge 278 is further rotated in the counterclockwise direction, since the set plate 282 is secured to the bridge 278 by the pin 281. Therefore, (1) The left end 280b of the continuous rotation instruction plate 280, secured to the

bridge 278 by a screw 279, moves down the shaft 290 carried by the motor release connector 75, so that when the release lever 168 is returned, the motor release connector 75 is lowered, whereby the release lever 168 moves to right thereby rotating the main shaft 59 again. However, when the release lever 168 is returned, the key stem 275 is released from the shaft 290 and returned to its initial position.

2. When the bridge 278 rotates in the counterclockwise direction, the zero setting plate 208 is moved to right by the right arm portion 278e of the bridge 278, so that the zero pins 11 in the digits in the pin box lower than a digit set in the pin box 8 are pushed whereby the carry mechanism, which is actuated when setting a number in the pin box 8, is released. Thus, the pin box 8 is advanced to a higher digit by the spring 261. The zero setting connecting lever 207 secured to the pin 209 of the zero setting plate 208 is also caused to move to the right, so that the right projection 207c of the plate 207 engages with the projection 293a of the hammer stop connecting lever 293 rotatably secured to the shaft 292, which in turn is fixedly secured to a motor bracket (not shown), whereby the hammer stop connecting lever 293 is caused to rotate in the clockwise direction. Therefore, the projection 293b of the hammer stop connecting lever 293 lifts the pin 294 of the hammer stopper 184, so that the stopper 184 is caused to move upwardly and, in the next rotation, the stopper 184 engages with the pin 295 of the hammer release bridge 115, thereby preventing the printing.

3. The pin box clear drive release lever 237 is rotatably secured to a pin 296 attached to the left arm of the bridge 278, guided by the pin 281 and is biased by a spring 297, so that it rotates in the counterclockwise direction about the pin 296. The projection 298a of the clear release lever 298 engages with the pin 238 of the pin box clear drive release lever 237 (see FIGS. 15 and 20) so that the pin box 8 is not cleared. These operations have been already described with regard to the multiplication mechanism.

4. Upon rotation of the bridge 278, the left arm 278a of the bridge 278 moves to the right the left end 300a of a division set slide plate 300, carried by two guide shafts 299 attached to the bottom of the machine frame 1. Referring to FIGS. 25A to 25D, two claws 303 and 304 are rotatably secured to the upper surface of the machine frame 1 through a pin 301, and are biased normally to rotate in the clockwise direction by a spring 302. When the division set plate 300 is not actuated (see FIG. 25A), one pawl 303 is prevented from rotating by a pin 305 of the connecting lever 234, in the clockwise direction, while the other pawl 304 has its end portion 304a abutted against the projection 300b of the division set plate 300 by the spring 302. When the division set plate 300 is moved upwardly (that is, from FIG. 25A to FIG. 25B), the end portion 304a is released from the projection 300b, so that the pawl 304 is released, thereby being rotated in the clockwise direction by the spring 302. In this case, the pawl member 304b of the pawl 304 engages with the projection 300b, so that even when the bridge 278 is returned to its normal position, as described in more detail hereinafter, the division set plate 300 is not returned, but is set to the position shown in FIG. 25B. Since the pin 305 remains stationary, the other pawl remains

unchanged. Referring to FIG. 19, when the pin box 8 is advanced to a higher digit, as described in (2) above, the curved portion 306a of a set plate 306 carried by the carriage 215 coupled to the pin box 8 engages with the curved portion 300c of the division set plate 300, so that the pin box 8 is stopped. This position of the pin box 8 corresponds to a position where the most significant digit of the pin box 8 is opposed to the most significant digit main rack 16. On the other hand, a roller 308, carried by a pin 307 of the division set lever 300, is released from a pin 310 of a shift-to-the-right drive plate 309, which may be moved transversely, guided by a pin 311 attached to the machine frame 1. When the division set lever 300 remains stationary, the drive plate 309 is pulled to the right, to an upper digit in FIG. 19, by means of a spring 314 between a pin 312 fixed to the drive plate 309 and a shaft 313 of the machine frame 1, but is prevented from moving to the right by the roller 308 of the division set lever 300, against which a pin 310 of the drive plate 309 (see FIG. 25A). A digit position setting pawl 316 is pivotably secured to a pin 315 of the machine frame 1 and is biased to rotate in the clockwise direction by means of a spring 319, between a pin 317 of the pawl 316 and a pin 318 of the machine frame 1. A pin 320 of the drive plate 309 pushes the right cam portion 316a of the pawl 316, so that the pawl is rotated in the counterclockwise direction, thereby preventing the pawl member 316b of the pawl 316 from engaging with a groove 322a of a shift-to-the-right grooved plate 322 secured to the carriage 215 by a screw 321. A shift-to-the-right pawl 324 is pivotably secured to a shaft 323, fixed to the drive plate 309, and is biased to rotate in the counterclockwise direction by means of a spring 327 extended between a pin 325 of the pawl 324 and a pin 326 of the drive plate. The pawl 324 abuts against a pin 328 of the machine frame 1 and is rotated in the clockwise direction against the spring 327, so that the pawl portion may be prevented from engaging with a groove 322a of the grooved plate 322, as in the case of the pawl 316.

A cam follower 329 is vertically reciprocated in FIG. 19 by a drive cam (not shown) which moves the drive plate 309 to the left, after the type bar 38 has reached its lowermost stroke position by the rotation of the main shaft 59.

When the cam follower 329 is lowered, it pushes an arm portion 331a of a drive plate drive lever 331, rotatably fixed to a shaft 330, which in turn is fixed to the machine frame 1, to rotate the drive lever 331 in the clockwise direction, thereby engaging the projection 331b of the drive lever 331 with the notch 309a of the drive plate 309. Therefore, the drive plate 309 is moved to the left.

When the cam follower 329 is moved upwardly, the drive plate 309 is moved to the right by the spring 314. However, when the drive plate 309 is moved to the left by the roller 308 of the division set lever 300, as described above, the drive plate 309 is moved away to the left, from the range where the cam follower 329 provides vertical reciprocation, so that the cam follower 329 will not engage with the drive plate 309. Thus, the drive plate 309 remains in stationary position. When the pin 310 of the drive plate 309 is released from the roller 308 of the division set plate

300, as described above, the state of the mechanism is shown in FIGS. 19 and 25B. In this case, the projection 309b of the drive plate 309 engages with the notch 300d of the division set plate 300, since when the cam follower 329 moves upwardly, prior to the upward movement of the type bar 38 in the next rotation, the drive plate 309 is moved to the right by the spring 314 through the drive lever 331. A pawl 334, which is pivotably secured to a pin 332 of the machine frame 1, and is biased to rotate about the pin 330 by a spring 333, in the clockwise direction, is caused to rotate in the counterclockwise direction, because the pin 310 of the drive plate 309 pushes the leading portion 334a of the pawl 334 when the division set lever 300 is not moved (see FIG. 25A), the projection 334b of the pawl 334 cannot engage with the notch 300d of the division set plate. When the drive plate 309 is moved to the right, however by the spring 314 (See FIG. 25B), the projection 334b of the pawl 334 engages with the notch 300e of the division set plate 300, so that the return of the division set plate 300 in the arithmetic operation preparation rotation may be prepared to be stopped, as described in more detail, hereinafter. Then, the left cam portion 316c of the pawl 316, pivoted to the shaft 315, abuts against a pin 335 of the drive plate 309, so that the pawl 316 is caused to rotate in the counterclockwise direction and will not engage with a groove 322a of the grooved plate 322. When the upper portion of the roller 308 of the division set plate 300 pushes the other end of an engagement preventive auxiliary lever 338, which is pivotably secured to the boss 337a of an engagement preventive lever 337, rotatably fixed to the shaft 313 of the machine frame 1, and one end of which is made to abut against a pin 339 fixed to the preventive lever 337, the preventive lever 337 rotates in the counterclockwise direction together with the auxiliary lever 338, so that the end 337b of the preventive lever 337 pushes the right arm portion of the pawl 324. In this case, the pawl 324 is prevented from being released plate 300, so that the pin 336 of the machine frame 1 abuts against the throat position 324b of the pawl 324, thereby rotating the pawl 324 in the clockwise direction. Therefore, the pawl 324 will not engage with a groove 322a of the grooved plate 322.

On the other hand, a connecting plate 342 is pivoted to a pin 341 of the division set 300 and has an elongated slot formed at the end remote from said pin 341. A pin 345 of a pawl stop lever 344 is fitted into the elongated slot. Therefore, when the division set lever 300 is in the state shown in FIG. 25B, the pin 345 is set free in the elongated slot of the connecting plate 342, so that the preventive lever 344 becomes free. One end of another connecting plate 346 is pivoted to the pin 345 of the preventive lever 344, while the other end thereof, pivoted to a pin 349 of an engagement instruction plate 348, whose one end is in engagement with the engagement instruction plate 225, and whose other end is pivotably secured to a pin 352 of a connecting plate 351, which is pivoted to a pin 349 of an engagement instruction plate 348, rotatably secured to an engagement instruction plate shaft 347, which in turn is secured to the machine frame 1, is pressed against the end portion of the elongated slot by a spring 350. Therefore, the both of the engagement instruction plates 225 and 348 are released. However, as described

in connection with the operation of the = key in the multiplication mechanism, the engagement instruction plate 225 remains stationary, so that the plates 225 and 348 are not released in practice.

5. When the set plate 282, shown in FIG. 24, is moved to the right, the projection 282e of the set plate 282 engages with a pin 353 of the cam follower set lever 137, so that the cam follower set lever 137 is caused to rotate about the projection 138a of the outer side plate 138 of the key board shown in FIG. 23. By this rotation, the caution pinion 152 is reset to zero when the type bar 38 is moved upwardly, as described in connection with the $\times$ key operation in the multiplication mechanism.

15. (see FIG. 24)

When the set plate 282 is moved to the right, the projection 282f of the set plate 282 pushes the arm portion 356a of a rotary plate 356, rotatably secured to a pin 355 of a pin box guide plate 354, shown in FIG. 23, so that the rotary plate 356 is rotated in the clockwise direction, thereby pulling to the left a connecting rod 357 fitted into the slot 356b of the rotary plate 356. Thus, the connecting rod 357, which is disposed in a hole of an engagement release plate 358, secured to the engagement auxiliary lever 161, secured to a pin 164 of the caution pinion grooved cam 146, causes the lever 161 to rotate in the clockwise direction about a shaft 162 (FIG. 26). However, as opposed to the $\times$ key 20 operation of the multiplication mechanism described hereinabove, the auxiliary lever 161 will not engage with a pin 166 secured to the caution pinion clear cam 144, so that no number is set in the caution pinions.

25. When the second rotation starts during the operations described in (1) to (6) above, the cam follower 286 is caused to rotate again in the clockwise direction by the dividend set cam 283. The pin 287 of the cam follower 286 disengages from the end 282d of the set plate 282 by the spring 359, so that the set plate 282 and the bridge 378 are returned to their initial positions. In this case, the release plate 168 is also returned to its initial position. Thus, all of the operations of the introduction mechanism are accomplished. In this case, the main shaft rotates twice.

Division Operation Mechanism

30. This is the mechanism for setting a divisor in the pin box, subtracting the divisor sequentially from the dividend starting from the most significant digit of the dividend which has been already set in the accumulator A, and setting the number of subtractions (the quotient) in the caution pinions 152.

35. During the execution of division, there is no printing on the paper 43, which is not advanced.

40. First, rotation is to prepare for executing the division. Next, the division (subtractions) is accomplished and the number of subtractions (quotient) are set to the caution pinions. The next rotation after the completion of the subtraction rotations, the pin box 8 is reset and in the further next rotation, a remainder is printed, thus accomplishing the division.

45. The operation of this mechanism is similar to that of the = key top 136 in multiplication described above, except the following:

50. 1. Referring to FIG. 14, the arithmetic operation set shaft 198 rotates in the clockwise direction, so that the

connecting lever 234 is moved to the right by the arm 232 carried by the shaft 198. Thus, as shown in FIG. 25A, the pin 305 of the connecting lever 234 pushes the cam portion 304a of the pawl 304, so that the projection 300b of the division set lever 300 is released from the projection 304b of the pawl 304. Then, by the engagement of the notch 300e of the division set lever 300 with the projection 334b of the pawl 334, the division set lever 300 is stopped. Since the pin 305 which has been in engagement with the cam portion 303a of the pawl 303 is displaced the pawl 303 is released, so that the projection 303b of the pawl 303 is moved to a position where it may engage with the projection 300b of the division set lever 300. In this case, the correlated operations of the selector 201, the pin box 8 and the carriage 215 are similar to those described in the multiplication operation. However, in multiplication, no number is set in the caution pinions 152, so that they are only moved until the selector 21 abuts against the flanged portion 152c of the caution pinion 152. In division, all of the caution pinions 152 are reset to zero, so that the pin box 8, the carriage 215 and the selector 201 are moved until the set plate 306, attached to the carriage 215, abuts against the projection 300c of the division set lever 300. This is illustrated in FIG. 19 and is similar to the state described in connection with the dividend introduction mechanism.

Next, at the end of the first rotation, the drive plate 309 is moved to left, so that the pawl 334 is released from the notch 300e of the division set lever 300 and the lever 300 is returned by a spring 360 extending between a pin 341 of the lever 300 and a shaft 299 of the machine frame 1 until the projection 300b abuts against the projection 303b of the pawl 303. (see FIG. 19). Then, the auxiliary lever 338, which has been in engagement with the roller 308 of the division set lever 300, is caused to rotate in the clockwise direction together with the engagement preventive lever 337, so that the auxiliary lever 338 is released from the arm portion 324c of the pawl 324.

As shown in FIG. 25D, when the drive plate 309 is moved to the right again, the projection 309b of the drive plate 309 abuts against the end 300f of the division set lever 300, so that the drive plate 309 is not permitted to move to the right any longer (see FIG. 19). Thus, the positioning pawl 316 cannot engage with the pin 335 of the left cam portion 316c, so that the pawl 316 is rotated in the clockwise direction by the spring 319, thereby engaging with one of the grooves 322a of the grooved plate 322. Also the throat portion 324b of the pawl 324 cannot engage with the pin 336, so that the pawl 324 is rotated in the counterclockwise direction by the spring 327, thereby engaging with the groove 322a of the grooved plate 322.

The throat portion 364b of the pawl 324 cannot engage with the pin 336, so that it rotates in the counterclockwise direction by the spring 327 and tends to engage with the groove 322a of the grooved plate 322. However, the pawl 324 engages with a pin 361 fixed to the preventive lever 344, which is moved through the connecting plate 346 by the instruction from the engagement instruction plate 225, so that the arm portion 324c is held in position. Thus, the projection 324a of the pawl 324 will not engage with the groove 322a of the grooved plate 322.

2. (see FIGS. 27A and 27B)

Upon rotation in the clockwise direction of the engagement instruction plate release arm 224, carried by the arithmetic operation set shaft 198, a release auxiliary lever 364, rotatably carried by the shaft 198, and in 5 abutment relation with the rear surface of the release arm 224 by its pin 362, due to a spring 363 rotates also in the clockwise direction. Then, an engagement direction instruction plate 366, which is rotatably carried by the caution pinion holder shaft 147, and is normally biased so as to rotate in the counterclockwise direction by a spring (not shown) between a pin 365 and the shaft 167, is stopped by the engagement of a pin 365 of an instruction lever 366, with an end 364a of an auxiliary lever 364, prior to the rotation in the 10 clockwise direction of the auxiliary lever 364. The arm 368a of a cam follower 368 which tends to rotate in the counterclockwise direction about the shaft 167 by a spring (not shown) due to the rotation of a cam 367, carried by the main shaft 59, is stopped by the pin 365 and is not permitted to move further. However, upon 15 rotation of the auxiliary lever 364, the pin 365 is released from the end 364a of the auxiliary lever 364, so that the instruction lever 366 is released whereby it may be rotated in the counterclockwise direction by the arm 368a of a cam follower 368.

a. When a positive number is set in the accumulator A, the credit balance stopper 94 is located as shown in FIG. 27A. Therefore, upon rotation of the cam follower 368 in the counterclockwise direction, the projection 366a of the instruction lever 366 engages with the lower portion of the credit balance stopper 94, so that the lever 366 is not permitted to rotate further. Therefore, the arm 368a of the cam follower 368 is stopped by the pin 365 and the arm portion 368b will not push the engagement instruction plate 225. That is, as shown in FIG. 19, by the spring 370 between a pin 369 of the machine frame 1 and a pin 345 of the preventive lever 344, the lever 344 is pulled so that the pawl 324 will not engage with the groove 322a, as shown in FIG. 19. The instruction plate 348 is rotated by the spring 370 in the clockwise direction, until it engages with the guide plate 371, so that the accumulator A is meshed with a minus accumulator pinion 46 and the subtractions are 20 started. On the other hand, the pin 226 of the engagement instruction plate 225 causes the caution pinion rotation direction instruction plate 228 to move upwardly through the caution pinion rotation direction instruction plate 227, until the pin 229 engages with the upper portion 231b of an aperture of the right side plate 231. Therefore, the caution pinion rotation direction instruction plate 228 is in the state shown in FIGS. 18C and 21, so that the caution pinions 152 are rotated in the direction opposite to that in case of the multiplication thereby setting a number to the caution pinions 152.

b. When a negative number is set in the accumulator A, the credit balance stopper 94 is in the position shown in FIG. 27B, so that upon rotation of the cam follower 368 in the counterclockwise direction, the instruction lever 366 will not engage with the credit balance stopper 94, but rotates in the clockwise direction. Therefore, the end 368b of the cam follower 368 engages with the engagement instruction plate 225, so as to rotate it in the clockwise direction. Then, the engagement instruction plate 225 is caused to move 25 downwardly in FIG. 19, so that the preventive lever

344 is rotated in the clockwise direction through the connecting plate 346, thereby releasing the pawl from the right arm portion 324c by the pin 361. Thus, the projection 324a of the pawl 324 engages with one of the grooves 322a, so that the pin box 8, the carriage 215 and the selector 201 are shifted to the right (to the lower digit) upon movement of the drive 309 to the left until the projection 316b of the positioning 316 engages with the next groove 322a.

On the other hand, the pin of the instruction plate 225 causes the pin 229 of the caution pinion rotation direction instruction plate 228 to move through the caution pinion rotation direction instruction connecting plate 227 until the pin 226 engages with the lower side 231a of the aperture of the right side plate 231, thereby deriving a number from the caution pinions 152, as in multiplication.

The divisor is sequentially subtracted from the most significant digit of a positive number set in the accumulator A by the key operation until the number becomes negative. The number of these sequential subtractions is set to the caution pinions 152 and when the number set in the accumulator A becomes negative, the caution pinions are rotated in the reverse direction through an angle corresponding to one tooth thereof, thereby adding the divisor. Thus, the number set in the caution pinions, that is, the number larger than the number of subtractions, by one, may be corrected by one tooth. At this time, the shift to the right, one position, is effected. Thus, the subtractions are continued until the least significant digit. When the shift-to-the-right is made after the subtraction at the least significant digit, the selector 201 is moved to the left, as shown in FIG. 28, and an operation termination instruction plate 373 is moved to the left along a pin 372 fixed to the machine frame 1. Therefore, a pin 374 of an instruction plate 372 rotates an operation termination lever 375 about a pin 376 fixed to the machine frame 1 in the clockwise direction, so that the slide plate 223 is moved to the right by an end 375a of the termination lever 375, thereby terminating the operation.

When a lever 378, which is rotatably secured to a pin 377 fixed to the machine frame 1, is rotated by the left end 372 of the instruction plate 372 in the counter-clockwise direction, a connecting plate 379, whose one end is pivoted to the lever 378 and whose other end is connected to a leg portion 265a of the lifting stopper 265, is moved to the right. Therefore, the lifting stopper 265 is moved to the right as in multiplication, so that the clear may be effected in the next rotation without moving the type bar 39 upward. Thus, the division is executed. As opposed to multiplication, in division, the pin box 8 is connected to the carriage 215 and the selector 201 and is only moved until the set plate 306 of the carriage 215 engages with the projection 300c of the division set plate 300. Therefore, the projections 176b and 177b of the continuous rotation slide plate 176, and the hammer stop side plate 177, shown in FIG. 15, will not engage with the selector 201, so that the slide plates 176 and 177 are not returned. Thus, the operation similar to the auto-total operation in the multiplication mechanism is accomplished and the remainder will be printed, thus completing the division. In this case, a quotient is set in the caution pinion gears 152. When the remainder is zero, the content in

the accumulator A becomes minus zero, even when an addition is made in the rotation immediately after the content of the accumulator A becomes negative. Therefore, the credit balance stopper 84 of FIG. 27 is placed in the state shown in FIG. 27B, so that the shift-to-the-right is effected in the next rotation and an addition is made in the position which is not shifted to right. Therefore, an erroneous answer will be obtained.

Therefore, when the cam follower 368 pushes the engagement instruction plate 225 two times, a switch (not shown) is turned on to actuate or energize a magnet device (not shown), thereby causing the pin shown in FIG. 28, to push the projection 381a of the lever 381 attached to the machine frame 1. Thus, the lever 381 is rotated in the counterclockwise direction and the termination instruction plate 372 is moved by the connecting rod 382, thereby terminating the division in the same manner as described hereinabove. Since the caution pinion 152 has the projection 152b shown in FIG. 13, upon one rotation of the pinion 152 (that is, when a number 10 is set), the projection 152b engages with the shaft 160 so that it is prevented from rotating further. Thus, the machine is locked. When the cam follower 368, which is stopped by the pin 365 of the engagement direction instruction lever 366, is rotated continuously ten times, the switch is turned on as in the case of the zero remainder, thereby terminating the division.

Quotient Reading Mechanism

This is a mechanism for reading the quotient in the caution pinions 152 and printing it. In this case, this mechanism is operated independently of the accumulator A.

Referring to FIG. 29, when a Q key stem 383 is rotated in the counterclockwise direction about a shaft 384, extending between the right and left outer side plates, a slide bridge 386, which is pivoted to a pin 385 of the Q key stem 383, and is guided by the shaft 67, is shifted to the right. In this case, a roller 387 of the grooved cam follower 68 is moved by a cam portion of the slide bridge 386, so that the grooved cam follower 68 is operated in order not to engage with the engagement cam 69, as in the case of X key operation in the multiplication mechanism.

Therefore, the accumulator A will not engage with the main rack 16. The cam 388, fixed to the bridge 386, moves a roller 391, fixed to a connecting bridge 390, for rotation about a shaft 389, so as to rotate the bridge 390 in the clockwise direction, thereby actuating a pin 393 of an engagement auxiliary plate 392 fitted into an elongated slot 390a of the bridge 390. Therefore, the auxiliary plate 392 is caused to move to the left with its leading portion being guided by the boss portion of the drive arm 148 while its elongated slot 392a is guided by a pin 394 of the caution pinion grooved cam 146. Thus, the projection 392b engages with the pin 145 fixed to the engagement direction indicating cam 90.

A release plate 396 pivoted to a pin 395 of the Q key stem 383 is lowered, so that a pin 397 of the release plate 396 causes the switch release lever 76 in the counterclockwise direction about the shaft 133.

Thus, the motor release connector 75 which is coupled to the switch release lever 76 is lowered, thereby actuating the release plate 168, so as to rotate the main shaft 59. Prior to the upward movement of the main

rack 16, the pin 145 of the cam 90 is made to engage with the projection 392b of the auxiliary plate 392, so as to move it further to the left. Then, a pin 398 of the auxiliary plate 392 engages with the caution pinion grooved cam 146, so as to rotate it in the clockwise direction about the shaft 167. As described in the X-key operation in the multiplication mechanism, the sub-rack 153 of the main rack 16 meshes with the caution pinion 152, so that the main rack 16 is moved upwardly, together with the type bar 38, until the projection 152b of the caution pinion 152 engages with the shaft 160, thereby printing a quotient. The main rack 16 is moved downwardly with the subrack 153 being in mesh with the caution pinion and the quotient (answer) is set into the caution pinion 152, which stores the quotient until the mechanism resetting the caution pinions is actuated by the X key or key operation.

Thus, the reading of the quotient is accomplished.

Some of the essential features of the present invention will now be described briefly. 20

1. A dividend and a divisor are so printed that the least significant digits of the effective numbers coincide with the least significant digit of an effective number to be printed in addition or subtraction. Thus, an operator 25 can check if the dividend and divisor have been correctly set in the machine and can see the true values thereof printed upon the paper, so that this is very convenient for checking if the calculations are correctly executed.

2. Since it is easy to check the true values of the dividend and divisor, it will be also easy to check the true value of a quotient.

3. Since the combinations of the parts in the multiplication and division mechanisms are made in a very sophisticated manner, the machine may be made very compact in size, which has not been attained heretobefore.

While the principles of the present invention have been made clear in the illustrative embodiments, there will be immediately obvious to those skilled in the art many modifications in structure, arrangement, proportions, the elements, materials and components used in the practice of the present invention and otherwise, which are particularly adapted for specific environments and operating requirements, without departing from those principles. The appended claims are therefore intended to cover and embrace any such modifications, within the limits only of the true spirit and scope of the present invention. 40

I claim:

1. A calculating machine for executing addition, subtraction, multiplication and division wherein a number set into the machine is printed as an effective number in accordance with the decimal orders of the calculating machine for visual observation in addition or subtraction, comprising

- a. a pin box having a plurality of movable pins therein,
- b. means for setting a number in said pin box,
- c. means supporting said pin box for shifting movement,
- d. means for printing a number set in said pin box,
- e. accumulator means for numbers set in said pin box, said accumulator means comprising pinions,
- f. caution pinion means,

g. means for transferring numbers set in said pin box to said accumulator means, said means comprising racks having heels engageable with set pins of said pin box, the pinions of the accumulator means being engageable by said racks,

h. means for transferring numbers set in said pin box to said caution pinion means,

i. means for preventing the transfer of numbers from said pin box to said accumulator means,

j. main shaft means,

k. keyboard means including division key means,

m. means responsive to movement of said division key means for effecting a first revolution of said main shaft means for actuating said pin box to set a number in said pin box and to prevent such transfer of the number to the accumulator means, for causing printing of the number set in said pin box with the least significant digit of an effective number of the dividend coinciding with the least significant digit of the effective number representing the first decimal order in addition or subtraction, and for thereafter permitting transfer of the number from said pin box to said accumulator means,

n. means responsive to the completion of said first revolution of said main shaft to cause a second revolution thereof, and

o. means responsive to the second revolution of said main shaft for shifting said pin box to a higher digit for preventing printing of the number set in said pin box, for stopping said pin box in a position in which the most significant digit of the effective number of the dividend is opposed to the most significant digit set in said accumulator means, for setting said caution pinions to zero, and for preventing the setting of a number in said caution pinions.

2. A calculating machine as claimed in claim 1, wherein said means for preventing the transfer of numbers from said pin box to said accumulator means comprises a non-addition plate, a lift lever for lifting said non-addition plate, and means engaged by said non-addition plate for removing the pinions of said accumulator means from engagement with the racks of said means for transferring numbers set in said pin box to said accumulator means.

3. A calculating machine as claimed in claim 1, 50 wherein the racks of said means for transferring numbers set in said pin box to said accumulator means are engageable with said caution pinion means.

4. A calculating machine as claimed in claim 1, wherein said means for printing a number set in said pin box comprises main racks having heels engageable with set pins of said pin box and type bar means carried by said racks.

5. A calculating machine as claimed in claim 1, 60 wherein said means for stopping said pin box in a position in which the most significant digit thereof is opposed to the most significant digit of said printing means comprises a division set slide plate, means for moving said division set slide plate, and means movable with said pin box for abutting said division set slide plate in one position thereof.

6. A calculating machine as claimed in claim 5, further comprising means for pushing zero pins of said

pin box which are lower than a digit set therein, and wherein said means for moving said division set slide plate actuates said means for pushing zero pins.
